United States Patent Office

Des. 177,721
Patented May 22, 1956

177,721

BANK OUTDOOR DEPOSIT WINDOW OR SIMILAR ARTICLE

Charles U. Deaton, Kirkwood, Mo., assignor to Diebold,
Incorporated, Canton, Ohio, a corporation of Ohio

Application January 12, 1955, Serial No. 33,933

Term of patent 14 years

(Cl. D13—2)

FIG. 1

FIG. 2

Fig. 1 is a perspective view of a bank outdoor deposit window or similar article showing my new design.

Fig. 2 is a partial vertical sectional view thereof.

I claim:

The ornamental design for a bank outdoor deposit window or similar article, substantially as shown.
